BABY BOTTLE NIPPLE PUNCH

Polly Nixon Slick, San Antonio, Tex., assignor to
 Institute of Inventive Research, San Antonio,
 Tex., a foundation of Texas

Application October 29, 1949, Serial No. 124,351

5 Claims. (Cl. 164—119)

1

The present invention concerns a punch device which can be used either by a manufacturer of baby bottle nipples to produce the openings of required size and arrangement, or by a mother or nurse, in which case the nipples are purchased without any openings, i. e., unperforated.

The greatest difficulty for the amateur parent lies in making the right size holes in the nipples. If the hole is too small, the baby will work and work and get nothing for his pains. He may get tired before he gets enough milk; if too large, the milk will come too fast and make him choke or have indigestion and he will get all his milk before he has sucked as long as he wants to. Getting the hole just right, therefore, is a matter of considerable importance. The milk should come out in large drops, one at a time, not run out in a stream. The usual procedure for an inexperienced mother or nurse in enlarging the hole or holes in a nipple is to insert the blunt end of a fine-pointed needle into a cork. The point of the needle is heated to a white heat. The eraser end of a pencil is usually inserted into the nipple to hold it out, then a hole is quickly burned with the needle point. The longer the hot needle is held against the nipple, the larger the hole will be. The hole is therefore enlarged gradually, trying the nipple each time until the hole is just large enough and not too large.

Obviously, a method of this sort is inefficient, a hit-and-miss affair, and as likely as not causes the spoilage of one or more nipples and there is considerable doubt if a nipple is ever obtained in this manner having exactly the right size hole and satisfactory arrangement of the openings. The same difficulties again arise when additional enlargements have to be made to accommodate the periodic modifications of the baby-feeding formula.

The present invention is intended to remove all guess-work from the procurement of these holes so that the latter can be punched in a non-perforated nipple to any desired shape, size and arrangement, and the holes can be enlarged in any predetermined and duplicatable manner.

In my application Serial No. 127,627 filed November 16, 1949, there is disclosed a baby bottle nipple in which the openings are of a clean-cut character and of strictly predetermined size and arrangement so that the nipple can be reproduced in quantity production with exact conformity to the shape, size and arrangement of the openings. Thus, these nipples can carry identifying insignia or be given arbitrary type, size and color or letters to indicate the size of the opening and the arrangement.

2

The primary object of the invention is to provide an improved punch, usable for making the openings of any predetermined size and arrangement in a baby bottle nipple, or a single opening in an unperforated nipple of unpredicted shape and size.

Another object is to provide a punch mechanism for increasing the size of the hole or holes in a perforated baby bottle nipple to accord with changes in the baby-feeding formula or in the rate of feeding.

Still another object is to provide a mechanism for perforating the ends of baby bottle nipples in a clean-cut, highly reproducible manner and without ragged or rough edges at the openings.

A further object is to provide an improved punching device for perforating baby bottle nipples and in which the openings are individually formed while the punch is moved relatively to the nipple to successive predetermined positions.

Another object is to provide an improved punching device for perforating the ends of baby bottle nipples and which can be manually operated with accurate reproducibility and duplication of the perforations as between the openings of each nipple, and as between the arrangement of openings between a plurality of nipples.

Other objects and features will be apparent as the specification is perused in connection with the accompanying drawings in which:

Figure 1 represents a side view of the improved nipple punch;

Figure 2 is an elevational front view of the same punch;

Figure 3 represents a plan view of the punch;

Figure 4 is an enlarged fragmentary view of the punching device, the main portions being shown in section. The section is enlarged and is taken at the line 4—4 in Figure 1; and

Figure 5 is a view taken at the line 5—5 in Figure 4, looking down the direction of the arrows but leaving off the lower base element.

In the drawings the dot-dash lines 1 (Fig. 1) represents the outline of a baby bottle nipple in which it is desired to produce fluid flow openings at the end of exact and reproducible area, shape and arrangement of openings. The nipple 1 may be constituted of natural or synthetic rubber and is fitted tightly over a formed support 2 (Fig. 4) which may be made of metal or plastic. This support surrounds, in a fairly snug manner, a metal rod or upright 3. This rod has secured thereto a knurled wheel 4, the arrangement being such that when the nipple 1 is snugly fitted over the support 2 the lower or flanged

portion of the nipple rests on the upper surface of the wheel. The rod is journaled at the lower end in a round plate 5 which sits on a ledge 6 within the hub 7 of a cylindrical base member 8. Thus the wheel 4 is adapted to be rotated on the bearings provided between the rod 3 and the plate 5, carrying with it the support 2 and the nipple 1.

The upper end of the rod 3 is provided with a number of countersunk openings 9 of a predetermined size, as will be explained hereinafter, these openings conforming to the desired arrangement of openings in the end of the nipple. Directly above the rod or die 3 there is a tapered punch 10 constituted of a rod and tapered to a point as indicated at 11. The position of the punch 10 is determined by the position of the openings 9, these openings being brought successively in register with the position of the tapered point 11 so that when pressure is exercised on the punch 10, this point pierces the end of the rubber nipple 1 and the point descends until it contacts with the upper periphery of each of the successively presented openings 9.

The nipple 1 is rotatively indexed by means of a click mechanism. This mechanism may comprise an annular groove 13 in the rod 3 at a position approximately midway of the thickness of the plate 5. At the bottom of the groove there is a plurality of equidistantly spaced hemispherical recesses 12, the number and position of these recessed being determined by the number and arrangement of the openings 9 in the rod. A pin 14 is continuously urged into these recesses 12 by a spring 15 held in position by means of a set screw 16 passing transversely through the plate 5. Thus, as the knurled wheel 4 is rotated, the rod 3 will index through successive positions determined by the radial movement of the pin 14 passing in and out of the successively presented recesses 13. Each time a recess is presented to the pin, the latter temporarily holds the rod 3 in that position and the openings 9 are so correlated with the position of the recesses that each opening is presented directly below the punch 10.

For manipulating the punch, any suitable form of support can be employed and a hand-operated knob provided at the upper end of the punch. However, in order to effect greater appeal, this support may take the form of fanciful birds or animals, a stork 17 being indicated as typical. The punch 10 passes through a vertical opening in the head of the support and terminates in a knob 18. This knob is positioned at a sufficient distance from the upper flat surface 19 of the support as to permit the pointed end 11 to be able to contact the upper edges of the recesses 9 in order to limit the downward movement of the punch and therefore precisely to determine the size of each opening formed in the nipple. When this registering contact is made between the punch and the opening 9, the angular position of the rod 3 as a result of the indexing movement, is automatically kept in positional register with the punch, since each opening is lined up with the tapered point during the successive piercing operations. However, it will be understood that, if desired, the limit of travel of the punch 10 can be determined solely by having the lower surface of the knob 18 contact the upper surface 19 of the support member.

While I have shown and described the punch as being constituted of a metal rod with a tapered point, it may be desirable to form the

punch as a small hollow tubing having a knife edge at the bottom so that when the knob 18 is depressed and the opening in the nipple made, any rubber chips will be forced into the bore of the tubing in order to insure a clean-cut surface at each opening.

After the requisite number of openings have been pierced or cut in the end of the nipple 1, the form 2 can be either lifted upwardly from the rod 3 on which it is held solely by a snug fit, or else if desired, the nipple itself can be removed from the support 2, leaving the latter in position and firmly secured to the rod. The contour of the support 2 is fitted to the natural shape of the nipple 1 so that there will be no stretch in the nipple when the openings are formed at the end. When these openings are formed in the manner described, they are clean-cut at the surface, with no ragged edges, and the size, shape and arrangement are of a strictly accurate and predetermined character since the taper of the punch 10, the travel of the punch and the indexing movement all remain the same between the aperture-forming operations on each nipple and as between successive nipples.

It is apparent that the size and arrangement of openings can be changed by replacing the rod 3 having openings of the requisite size and arrangement and also modifying the relative positions of the recesses 13 which register with the pin 14 as the wheel 4 is rotated.

In the event it is desired to make only one opening in an un-perforated nipple, or if the size of an existing opening need be enlarged to conform, perhaps, to a change in the feeding formula, the rod 3 may be provided with openings 9 of different sizes and rotating the wheel 4 until the proper size opening is presented to the punch 10. The latter can then be de-pressed as far as it will go to leave a single hole of proper size. The openings in the rod 3 may be suitably designated so as to inform the user as to the opening size that will be obtained for a given movement of the wheel 4.

I am aware that the invention may be embodied in still other specific forms without departing from the spirit or essential attributes thereof, and I therefore desire the present embodiment to be considered in all respects as illustrative, and not restrictive; reference being had to the appended claims rather than to the foregoing description to indicate the scope of the invention.

Having thus fully described my invention, what I claim as new and desire to secure by Letters Patent, is:

1. A device for perforating baby bottle nipples, comprising a rotatable upright, a body surrounding said upright and secured thereto, said body conforming to the shape of the nipple including the end thereof, an indexing mechanism operatively associated with said upright, an indexing wheel secured to said upright for operating said mechanism, openings in the end of the upright adjacent the end of the nipple, a punch secured to said device in register with the openings in said upright as the last mentioned is indexed, said punch serving to make holes in the ends of the nipples at successive positions as the upright is indexed and the punch is de-pressed at each indexed position.

2. A device for perforating baby bottle nipples comprising a hollow cylindrical support for the nipple, including a base member, a cylindrical bearing contained within said support, said

bearing comprising a metal plate having a centrally disposed opening, a rod rotatably extending through said opening, a wheel attached to and surrounding said rod for rotating the rod, said wheel resting on said base member, an indexing mechanism operated by said wheel and cooperating with said cylindrical bearing member and the rod for imparting to the rod an angular motion when the wheel is turned, the upper end of said rod being adapted to receive the end of the 10 nipple to be perforated, said end of the rod having a series of longitudinally extending openings of predetermined size depending on the size of the perforations to be made in the nipple, and a punch mechanism presented to each of said openings in succession as the rod is indexed, the punch having a tapered end and adapted to pierce the nipple at successive positions corresponding to the positions of said openings and depending on the angular movement of said rod.

3. A device for perforating baby bottle nipples comprising a hollow cylindrical support for the nipple, including a base member, a cylindrical bearing contained within said support, said bearing comprising a metal plate having a centrally disposed opening, a rod rotatably extending through said openings, a wheel attached to and surrounding said rod for rotating the rod, said wheel resting on said base member, an indexing mechanism operated by said wheel and cooperating with said cylindrical bearing member and the rod for imparting to the rod an angular motion when the wheel is turned, the upper end of said rod being adapted to receive the end of the nipple to be perforated, said end of the rod having a series of longitudinally extending openings of predetermined size depending on the size of the perforations to be made in the nipple, and a punch mechanism presented to each of said openings in succession as the rod is indexed, the punch having a tapered end and adapted to pierce the nipple at successive positions corresponding to the positions of said openings and depending on the angular movement of said rod, and a support having a configuration of the interior shape of the nipple surrounding said rod and resting on said wheel, said support being adapted to rotate when the rod is indexed through the successive angular positions.

4. A device for perforating baby bottle nipples comprising a hollow support for the nipple, a bearing contained within said support, a rotatable rod in said bearing, said rod being adapted to receive that portion of the nipple to be perforated, an indexing mechanism for rotating the rod through predetermined angles, said mechanism including a peripheral groove in the rod

and inwardly extending depressions at the base of the groove, a spring-urged pin extending toward said groove and adapted successively to enter any one of said depressions, a hand-operated wheel for rotating the rod in said bearing and causing the pin to move into and out of the depressions successively whereby the rod is indexed, openings at the end of the rod adjacent the nipple, said openings corresponding in angular position with the depressions at the base of said groove, and a punch positioned directly above the position of each of said openings as the rod is indexed, said punch being adapted to be de-pressed at each indexed position of the rod and to form a fluid flow opening in the nipple.

5. A device for perforating baby bottle nipples comprising a hollow support for the nipple, a bearing contained within said support, a rotatable rod in said bearing, said rod being adapted to receive that portion of the nipple to be perforated, an indexing mechanism for rotating the rod through predetermined angles, said mechanism including a peripheral groove in the rod and inwardly extending depressions at the base of the groove, a spring-urged pin extending toward said groove and adapted successively to enter any one of said depressions, a hand-operated wheel for rotating the rod in said bearing and causing the pin to move into and out of the depressions successively whereby the rod is indexed, openings in the end of the rod adjacent the nipple, said openings corresponding in angular position with the depressions at the base of said groove, and a punch positioned directly above the position of each of said openings as the rod is indexed, said punch being adapted to be de-pressed at each indexed position of the rod and to form a fluid flow opening in the nipple, said punch having a tapered end and when being de-pressed to pierce the nipple moves downwardly to such extent that the tapered periphery of the punch comes into contact with the upper periphery of the openings in said rod.
